UNITED STATES PATENT OFFICE.

ALFRED A. ZIEGLER, OF BOSTON, MASSACHUSETTS.

RELAY.

1,204,835.

Specification of Letters Patent.

Patented Nov. 14, 1916.

Application filed May 22, 1915. Serial No. 29,903.

To all whom it may concern:

Be it known that I, ALFRED A. ZIEGLER, a citizen of the United States, residing at Boston, in the county of Suffolk, in the State of Massachusetts, have invented an Improvement in Relays, of which the following is a specification.

This invention relates to electro-magnetic apparatus well adapted for use in relays such as used in connection with railway signaling apparatus, and shown in my applications Serial Nos. 534,932, and 740,775. In this type of relay it is desirable to arrange the magnet-cores in upright position on a carrying-plate which forms the top wall of a sealed housing, and to permanently and securely fasten them to said plate, to provide removable magnet-coils, to provide means for securing the magnet-cores to the carrying-plate which are accessible from within the housing to prevent the relay being tampered with, and to construct the securing-means for the cores so that they will not occupy a position in the magnetic fields of their poles. In this type of apparatus it being desirable to use as small a current as possible for purposes of economy, the magnet-cores have enlarged pole-pieces.

My present invention has for its object the provision of improved means for conveniently and securely fixing the magnet-cores equipped with such pole-pieces to the carrying-plate, whereby the above results may be accomplished.

Referring to the drawings: Figure 1, is a front elevation of a relay showing one embodiment of my invention. Fig. 2, is a fragmentary sectional view showing my improved securing-means for the magnet-cores. Fig. 3, is an enlarged detail elevation of the securing-means. Fig. 4 is an enlarged sectional view of the securing-means.

The carrying-plate of the relay which forms the top wall of a sealed housing is here shown as a two-part element similar to that shown in my application #740,775, it comprising an upper part 1, which may be a slab of insulating material, such as porcelain, and an under part 6, which may be a metallic plate, the latter being secured to the underside of the former by clamping-bolts 7, the nuts of which are countersunk in the plate 1, as at 8. The carrying-plate bears any desired number of upwardly disposed binding-posts 2, and an uprightly disposed operating-magnet for the relay-con-

tacts, which latter are arranged within the sealed housing, as well as the armature of said magnet. The cores 4-4 of the magnet are stationarily supported on said carrying-plate and the coils of said magnet are removably placed on said cores, and said cores have enlarged pole-pieces 9. The carrying-plate has aligned holes through its component parts for the magnet-cores 4-4, so that the pole-pieces 9, thereof will occupy positions within the housing while the main portions thereof extend above the carrying-plate to receive upon them the magnet-coils.

A two-part carrying-plate is not herein claimed, and in so far as some of the features of my invention are concerned, a one-part carrying-plate, as shown in my application #534,932, may be employed, but the present invention is more especially designed for use in connection with a two-part carrying-plate, and many advantages are gained by its use in connection therewith.

In carrying out my invention the metallic plate 6 is formed with threaded holes 10, somewhat larger than the cores 4, which pass therethrough, and in these holes, at the upper side of the plate, or that side adjacent the plate 1, are threaded ring-nuts 11, which are adapted to slip over the cores 4. These nuts have flanged heads 12, arranged in recesses in the underside of the plate 1. Each core 4 is provided with a circumferential groove 13, which is arranged substantially opposite the top of the head 12, when the ring-nut 11, is assembled, as described, and the top of said head is cut away into the central passage, as at 14, to form in cooperation with the groove 13, an annular recess. In said recess is placed a ring 15 of hard wire or the like, to form an enlargement on the core, this typifying any suitable kind of abutment adapted to be conveniently associated with the core to permit the ring-nut 10 to react against the core 100 for moving said core longitudinally upon turning the nut. Upon the insertion of this ring 15, the ring-nut 11, may be turned backward to a small extent, and by its engagement therewith will draw up the core 105 until its pole-piece 9, snugly engages the under face of the plate, this serving to securely clamp and hold the core to the plate 6. The plate 6, with the cores thus rigidly assembled therewith, may be applied to the 110 upper plate 1, and bolted thereto by the bolts 7, with the cores projecting through said

plate in operative position. It is to be observed that not only is the described securing-means of simple and effective character adapted for the quick assembling of the 5 parts, but there is no interference with the magnetic field of the pole, and furthermore, the securing-means is concealed between the two-parts of the carrying-plate, and therefore very inaccessible, and only accessible 10 when the housing and metallic plate are removed.

The invention is not to be understood as restricted to the specific form shown since manifestly equivalents as to details thereof 15 may be adopted without departing from the essential attributes, and I, therefore, desire the present embodiment to be considered as essentially illustrative.

- I claim:—
- 20 1. In a relay, a carrying-plate, an electro-magnet core extended through said plate, and having at its inner end an enlarged pole-piece, a ring-nut adjustably secured to said plate, and arranged on said core, and re-25 movable means arranged on said core, above said nut, against which said nut reacts to adjust said core longitudinally to draw the pole-piece into engagement with the plate, and thereby clamp the core stationarily to 30 the plate.
  2. In a relay, a carrying-plate, an electro-magnet core extended through said plate and having at its inner end an enlarged pole-piece, removable means arranged on the 35 core above the plate and adapted to project therefrom to form a shoulder, and an annular element arranged on the core between the shoulder and the plate, said annular element and said plate being provided with 40 interengaging means for moving them rela-

tive to each other so as to move the core longitudinally to draw the pole-piece into engagement with the plate, and thereby clamp the core stationarily to the plate.

3. In a relay, a carrying-plate, an electro-45 magnet core extended through said plate and having at its inner end an enlarged pole-piece, a ring-nut threaded in said plate and arranged on said core, and an insertable backing-member adapted to be applied to 50 said core to permit said nut to react thereagainst for clamping said core to said plate.

4. In a relay, a carrying-plate, an electro-magnet core extended through said plate and having at its inner end an enlarged pole-55 piece, a ring-nut threaded in said plate and arranged on said core, said core and said nut having co-operative grooves to form an annular recess, and an element arranged in said recess to serve as a backing against 60 which said nut may react for clamping said core to said plate.

5. In a relay, a carrying-plate, an electro-magnet core extended through said plate and having at its inner end an enlarged 65 pole-piece, a ring-nut threaded in said plate and arranged on said core, said nut having an enlarged head, and said core being formed with an annular groove substantially opposite the top of said nut, and a 70 ring-member arranged in said groove to serve as a backing against which said nut may react.

In testimony whereof, I have signed my name to this specification, in the presence of 75 two subscribing witnesses.

ALFRED A. ZIEGLER.
